UNITED STATES PATENT OFFICE.

SAM WESTERHEIM, OF SIOUX FALLS, SOUTH DAKOTA.

WINDOW CONSTRUCTION.

Application filed April 20, 1928. Serial No. 271,557.

This invention relates to window constructions and the primary object thereof is to provide an improved structure which eliminates the commonly employed ropes, weights and pulleys.

The invention further aims to provide a window construction wherein the means for holding the window in its adjusted position also functions as a weather strip to exclude air and moisture.

A still further object of the invention is to provide a structure which enables the usual guiding strips to have a loose fit with the sides of the window thereby to eliminate sticking of the window caused either by swelling of the parts or the collection of paint or varnish.

The invention still further aims to provide a simple and economical construction which can be easily applied and which occupies a minimum of space.

In the drawings:

Fig. 1 is a horizontal section of the invention, one of the windows being omitted;

Fig. 2 is a side elevation with both of the windows omitted;

Fig. 3 is a fragmentary front elevation of one of the windows, partly broken away and in section;

Fig. 4 is a detail perspective view of the member that is attached to the window casing;

Fig. 5 is a like view of the member that is attached to the window, and

Figs. 6 and 7 are like views of the spring and the end seal of the window member respectively.

In proceeding in accordance with the present invention, the side edges of the windows are longitudinally grooved as indicated at 1 to receive the U-shaped members 2 therein, the sides of the members being formed with outwardly extending flanges or wings 3, which latter are disposed in spaced relation to the said side edges of the window. Substantially

right angular sealing clips 4 are disposed at the ends of the members 2 and have their ends 5 closing the ends of the members, while their ends 6 are secured by means of screws 7 to the windows. Curved plate springs 8 are dis-

posed within the U-shaped members and have their free ends bearing against the bottom-forming portions of the members and are secured in position by means of bolts 9 which latter extend through openings provided

therefor in the central portions of the springs. The bolts pass through the side stiles of the

window and have their heads exposed so as to be readily accessible for purpose of adjustment of the tension of the springs.

Complementary members 10 are secured to the window casing in the usual guides defined by the guiding strips 11 and are provided with inwardly turned sides 12. The flanges 3 of the members 2 are disposed adjacent to the bases of the members 2 and the inturned sides 12 of the members 10 are engaged over the flanges 3 of the members 2, so that such flanges are enclosed by the sides 12 of the members 10. Preferably the central portions 13 of the members 10 are provided with longitudinal inwardly extending beads or hollow ribs 14 the interiors of which receive suitable packing strips 15. The packing engages the bottoms of the window guides and is held in sealing engagement therewith by means of screws 16 or equivalent fasteners which are driven through the ribs 14 and into the window casing.

From the foregoing it will be seen that the sides of the members 10 are free for flexing movement, due to the central securement of the members. As depicted in the drawings, the bases of the U-shaped members 2 are normally spaced from the bottoms of the grooves 1, and are under the tension of the springs 8 which latter act to draw the members 2 and thereby their flanges or wings 3 against the inturned sides 12 of the members 10. Thus the two members are held under constant tension and hence in frictional engagement, which latter is of such nature or degree to maintain the windows against vertical movement in any position thereof.

It will further be apparent that a complete seal is provided against the ingress of air or moisture by virtue of the two members. In this regard, it will be seen that the packing strip positively prevents passage of air etc., while the interengagement of the parts 3 and 12 and the action of the spring in holding the parts 12 against the side edges of the window, due to the spring forcing the parts 3 against parts 12, air etc., is likewise prevented from passing.

Additional fasteners 17 may be provided for the members 2 if desired and which act as guides for the same as shown in Fig. 3.

What is claimed is:

1. In combination with a window having a groove in its side edge and a casing having a window guide, a substantially U-shaped member in said groove having outwardly

extending flanges disposed over and spaced from the said side edge of the window, curved plate springs in the U-shaped member having its free edges bearing against the bottom of the member, bolts extending through the springs and member and through the window sides so as to be accessible for adjustment, a member having a base engaged with the bottom of the guide and having inturned sides, said flanges of the first member being received between the base and inturned sides of the second member, said second member having a central longitudinal hollow inwardly extending bead, a packing strip in the bead engaged with the bottom of the guide, and fasteners extending through the bead and into the casing.

2. In combination with a window having a groove in its side edge and a casing having a window guide, a substantially U-shaped member in said groove having outwardly extending flanges disposed over and spaced from the said side edge of the window, spring means to secure said member to the window and to urge the same toward the member, a member having a base engaged with the bottom of the guide and having inturned sides, said flanges of the first member being received between the base and inturned sides of the second member, said second member having a central longitudinal hollow inwardly extending bead, a packing strip in the bead engaged with the bottom of the guide, and fasteners extending through the bead and into the casing.

3. In combination with a window having a groove in its side edge and a casing having a window guide, a substantially U-shaped member in said groove having outwardly extending flanges disposed over and spaced from the said side edge of the window, a second member having a base secured to the bottom of the guide and having inturned sides, said flanges of the first member being received between the base and inturned sides of the second member, and spring means to tension the first member to urge same toward the window thereby to press the flanges of

the first member against the inturned sides of the second member.

4. In combination with a window having a groove in its side edge and a casing having a window guide, a substantially U-shaped member in said groove having outwardly extending flanges disposed over and spaced from the said side edge of the window, a second member having a base secured to the bottom of the guide and having inturned sides, said flanges of the first member being received between the base and inturned sides of the second member, spring means to tension the first member to urge same toward the window thereby to press the flanges of the first member against the inturned sides of the second member, and means to secure the base of the second member to the bottom of the guide disposed centrally of the width of the second member so as to leave the sides of the base and the inturned portions thereof free for flexing movements.

5. In combination with a window and its guide, a member having a base and inturned sides, means to secure the base to the guide so as to leave the inturned sides thereof free for flexing movements, said window having a grooved side edge, a second member in the groove having portions disposed without the groove and received between said base and the inturned sides of the first member, and spring means in the groove to tension the second member thereby to hold its said portions against the inturned sides of the first member.

6. In combination with a window and its guide, a member secured to the guide, said window having a groove in its outer side edge, a second member, said members having slideable interengaging portions, means in the groove to tension the second member thereby to hold said interengaging means under tension, and means operable from the inner side edge of the window to adjust the tension of said tensioning means.

In testimony whereof I affix my signature.

SAM WESTERHEIM.
